CLAIM

The ornamental design for a foot operated toilet seat lifter, as shown and described.

DESCRIPTION

FIG. 1 is an environmental perspective view of a foot operated toilet seat lifter showing my new design; FIG. 2 is a front elevational view thereof; FIG. 3 is a rear elevational view thereof; FIG. 4 is a left side elevational view thereof; FIG. 5 is a right side elevational thereof; FIG. 6 is a top plan view thereof; and, FIG. 7 is an environmental left side elevational view thereof. The broken line showing of the toilet in FIGS. 1 and 7 is for illustrative purposes only and forms no part of the claimed design. The undisclosed bottom view is unornamented.
